US0D1109876S

(12) **United States Design Patent** (10) Patent No.: **US D1,109,876 S**
(45) Date of Patent: ** Jan. 20, 2026

(54) **NON-ADHERENT DRESSING OR BANDAGE FOR BREAST CANCER RADIATION TREATMENT**

Primary Examiner — Michael A. Pratt

(71) Applicant: **Darnella Banks**, Englewood, NJ (US)

(57)

CLAIM

(72) Inventor: **Darnella Banks**, Englewood, NJ (US)

The ornamental design for a non-adherent dressing or bandage for breast cancer radiation treatment, as shown and described.

(**) Term: **15 Years**

(21) Appl. No.: **29/966,135**

DESCRIPTION

(22) Filed: **Sep. 30, 2024**

FIG. 1 is a front elevation view of the contoured dressing/bandage for the left side, showing the ornamental design characterized by a dome-like central body with gently flared edges extending outward;

(51) LOC (15) Cl. **24-04**

FIG. 2 is a side elevation view thereof;

(52) U.S. Cl.

FIG. 3 is a front elevation view of the dual configuration thereof;

USPC **D24/189**

FIG. 4 is a front elevation view of the right breast bandage thereof;

(58) **Field of Classification Search**

FIG. 5 is a side elevation view of the right breast bandage, thereof;

USPC D24/189-190

FIG. 6 is a top plan view of the dual configuration thereof;

CPC A61F 13/145; A61F 2013/15016; A61F

FIG. 7 is a bottom plan view of the dual configuration thereof;

13/14; A61F 13/45; A61F 2013/00217;

FIG. 8 is a rear elevation view of the dual configuration thereof; and,

A61F 13/00; A61F 13/0236

FIG. 9 is an isometric perspective view of the dual configuration thereof.

See application file for complete search history.

In this description, the broken lines shown in the FIGS. 1-9 depict portions of the non-adherent contoured dressing/bandage for breast cancer radiation treatment in which the design is embodied that form no part of the claimed design patent.
